UNITED STATES PATENT OFFICE.

SAMUEL G. CABELL, OF WASHINGTON, DISTRICT OF COLUMBIA, ASSIGNOR
TO FLORA B. CABELL, OF SAME PLACE.

LUBRICATOR.

SPECIFICATION forming part of Letters Patent No. 283,860, dated August 28, 1883.

Application filed March 26, 1883. (No model.)

To all whom it may concern:

Be it known that I, SAMUEL G. CABELL, of Washington, in the District of Columbia, have invented certain new and useful Improvements 5 in Lubricators; and I do hereby declare the following to be a full, clear, and exact description of the same, reference being had to the accompanying drawings, forming a part of this specification, and to the figures and letters of 10 reference marked thereon.

This invention relates particularly to that class of lubricators known as "overflow-cups;" and it consists in several novel improvements, which I will first describe and then point out 15 particularly in the claims at the end of this specification.

Referring to the accompanying drawings, Figure 1 represents a longitudinal vertical section of an oil-cup constructed in accordance 20 with my invention. Fig. 2 is a similar view of a modified form of cup.

Similar letters of reference in the accompanying drawings indicate the same parts.

A indicates the body of the exterior shell of 25 the cup, preferably of cylindrical form, with its lower end, B, rounded or beveled down toward the center, and having formed with it or connected to it a hollow stem, C, by which the cup is attached to the steam-chest or other 30 part to be lubricated.

Arranged within the outer shell, A, and secured to it by a screw-connection, d, at the upper end, is an interior shell, D, adapted to contain the oil or other lubricant. This shell 35 D is of less diameter than the internal diameter of the shell A, and its lower end extends down near to, but not in contact with, the lower end of said shell A, thus leaving a free open space, S, between the two shells at the 40 sides and bottom all around.

E represents the upper part or cap of the outer shell, the same being united to the upper projecting portion of the inner shell, D, by a screw-connection, and bearing down upon 45 the upper end of the body of the outer shell. A washer, F, is interposed between the cap and the inner shell or cup to secure a tight joint. The bottom of the inner shell, at the center, is provided with a conical perforation, 50 G, in which is adapted to closely fit the lower end of a valve-stem, H, which has near its up-

per end a screw-threaded portion, h, which works in a correspondingly screw-threaded portion e of the cap E. To the extreme upper end of the stem H is connected a feed-cup, I, 55 which is normally covered by a tightly-fitting cap, J, forced down by a screw-stem, K, working through a yoke, L, secured to flanges in the feed-cup I by screws M M, as shown. By loosening one of the screws M and raising the 60 cap J, so as to clear the flange on feed-cup I, the yoke L can be swung to one side, carrying the cap J with it, thus permitting oil to be poured into the feed-cup I. There is a channel, N, leading down through the stem H from 65 the feed-cup I to the interior of the inner shell, D, so that oil poured into the feed-cup will be conducted into the inner shell or oil-reservoir. Provision is thus made for filling the oil-reservoir. A suitable packing-gland, O, preserves 70 a tight joint between the valve-stem and the cap E.

P represents a cock tapped through both the outer shell, A, and inner shell, D, and having an upwardly-bent pipe, Q, attached to the 75 inner end of its shank, and having also an opening, R, in its shank leading into the space S between the shells, as shown. The valve-stem T of the cock P, when screwed in, closes communication between the space S and the 80 interior of the oil-reservoir D; but when screwed out, both the end of the pipe Q and the opening R are uncovered, thus establishing communication between such reservoir and space. 85

When the lubricator, constructed as above, and with its inner shell or oil-reservoir filled with oil or other lubricant, is applied to the steam-chest of an engine and steam admitted to it, the steam will at once fill the space S 90 and surround the sides and bottom of the oil-reservoir, thus thoroughly heating the contents of said reservoir and bringing it to a condition calculated to insure its ready flow. If now the valve-stem T be screwed outward, 95 steam will pass through opening R and pipe Q into the upper part of the oil-reservoir, and there will become condensed by contact with the cap E, and the resulting water of condensation will gradually displace the oil in the reservoir, 100 and the oil will pass out through said pipe Q and opening R into the steam-space and down

through the latter into the stem C, and thence into the steam-chest. The quantity of oil fed can, of course, be regulated by adjustment of the valve-stem T.

5 To vary the condensing effect of the cap E it is only necessary to enlarge or decrease its condensing surface, which can be done by making the cap larger or smaller. When the oil in the reservoir has been entirely displaced by 10 the water of condensation, the latter may be drawn off and caused to pass down the stem C by turning the main valve-stem H so as to raise it from its seat G.

Where there is no pressure of steam in the 15 space S, oil may be fed by gravity from the reservoir down through the stem C by adjustment of the valve-stem H. The same lubricator, it will thus be seen, may be worked either upon the gravity or overflow principle.

20 The modification shown in Fig. 2 embodies the overflow principle of feeding, the steam-space S, between the inner and outer shells and the pipe Q, being substantially the same as shown in Fig. 1. The oil is fed in through 25 a stem, U, controlled by a valve, V. A petcock, W, is provided in the cap E, and hollow plugs X y lead into the inner shell or oil-reservoir, and communication is established between them by a glass gage-tube, Z, as shown. 30 This tube serves to indicate the height of oil in the reservoir. The water of condensation may be drawn off by opening a cock, 3, in the lower plug, y.

Having thus described my invention, I claim 35 as new—

1. In an overflow oil-cup, an oil-reservoir jacketed and heated by steam, and having an overflow-channel leading into the steam-supply, substantially as described.

40 2. In an overflow oil-cup, the combination

of an outer casing or shell, an inner shell constituting an oil-reservoir, arranged within the outer shell with a steam-space between the two, an overflow-channel leading from the oil-reservoir to the steam-supply, and a valve for 45 controlling the discharge through said channel, substantially as described.

3. An oil-cup consisting of the following elements: the outer shell, the inner steam-jacketed shell, constituting, with its cap, the oil-reservoir, the hollow valve-stem, through which the reservoir is filled, and means, such as described, for closing the upper end of the hollow valve-stem, substantially as described. 50

4. An oil-cup consisting of the following elements: the outer shell, the inner steam-jacketed shell, constituting, with its cap, the oil-reservoir, and having the opening in its bottom, with the valve for controlling the discharge of oil through said opening in the bottom of 60 the oil-reservoir, whereby oil may be permitted to gravitate through said opening into the steam-space, substantially as described. 55

5. An oil-cup consisting of the following elements: outer shell, the inner steam-jacketed 65 shell having the opening in its bottom, the valve for controlling said opening, the overflow-channel connecting the reservoir with the steam-supply, and the valve for controlling said channel, said construction permitting 70 either an overflow-feed through the overflow-channel or a gravity-feed through the opening in the reservoir-bottom, according to the adjustment of the valves, substantially as described.

SAMUEL G. CABELL.
